UNITED STATES PATENT OFFICE.

JOHN F. GRABILL, OF FLORA, ILLINOIS, ASSIGNOR OF ONE-THIRD TO EARL ARBUTHNOT
AND ONE-THIRD TO HORATIO C. CHAFFIN, BOTH OF FLORA, ILLINOIS.

DRILL-SOCKET.

1,256,222.

Specification of Letters Patent. Patented Feb. 12, 1918.

Application filed March 14, 1917. Serial No. 154,849.

To all whom it may concern:

Be it known that I, JOHN F. GRABILL, a citizen of the United States, residing at Flora, in the county of Clay and State of Illinois, have invented certain new and useful Improvements in Drill-Sockets, of which the following is a specification, reference being had to the accompanying drawings.

This invention relates to sockets for rotatable drills, reamers, and like tools.

Sockets of this character are made in sets, each set comprising a plurality of sockets. Originally all of these sockets of a set were hollow, tapered, and annular in form to provide a tapering bore extending longitudinally of the socket. Each socket tapered uniformly from one end to the other, except at the inner end where they were reduced in thickness and all that portion of a socket which is hollow has a wall of uniform thickness. The sockets of a set were graduated, as to size, so that they nested, one within the other. Originally all the sockets of a set were annular in cross section, that is, the inner wall was circular and concentric to the outer wall. Each one of these sockets was adapted to receive a drill of the proper size.

Later there came into use, a form of socket called the "Use 'em' up" socket, designed for engagement with the drill only, these sockets being formed in graduated sizes, each socket having a flattened tapering portion on its inner face to engage with the flattened portion of a drill and cause the unitary rotation of the drill with the socket. This last named socket was eventually associated in use with the original round socket but as a drill holding socket exclusively, and when this "Use 'em' up" socket is used in conjunction with the set of round sockets, it required an extra socket for each of the different sizes of the "Use 'em' up" socket. The round socket and the last named socket are not sold with each other in sets but they are separately purchased and used together. The "Use 'em' up" socket, however, was used only as the socket which engages or holds the drill. A disadvantage of this construction lies in the fact that for each set of these "Use 'em' up" or drill sockets, five of the old type round sockets must be used as reducers in order to reduce to the size of the drill used so that a complete set of sockets consists of five round sockets and

five drill or "Use 'em' up" sockets associated with the old form of socket. Another disadvantage which is present in both forms of the sockets above described is that the socket, having a wall of uniform thickness from its lower end to its upper end is very liable to break at the mouth of the socket.

One of the objects of my invention is to reinforce the wall of the socket at its mouth so as to stand the strain to which it is subjected, thereby very greatly increasing the life of the socket and a further object is to so construct the sockets that any one may be used either as a drill socket or as a reducer socket, the several sockets being adapted to engage with each other or the drill.

Other objects will appear in the course of the following description.

My invention is illustrated in the accompanying drawings, wherein:

Fig. 1 is an elevation of a plurality of sockets and a drill, the sockets being constructed in accordance with my invention, a drift bar being shown in dotted lines;

Fig. 2 is a vertical sectional view of the larger socket B on the line 2--2 of Fig. 1, the other sockets being shown in elevation; and

Fig. 3 is a section on the line 3--3 of Fig. 2.

Referring to these drawings, it will be seen that my improved socket comprises a tapering body 10 reduced in thickness at its upper end as at 11 as usual, this tapering body being formed with a correspondingly tapering bore 12. The lower end of the socket body is thickened as at 13 so that the wall surrounding the lower portion of the bore 12 is approximately twice as thick as the wall surrounding the upper portion of the bore above the reinforced or thickened portion 13. This thickened wall 13 is approximately of uniform diameter. The body 10 is formed intermediate its ends with the transverse slot 14 which intersects the bore and provides means whereby the drill may be driven out of the socket or one socket may be driven out of another socket.

The bore 12 is not truly circular but the inner face of the wall surrounding the bore is formed with a flat portion 15, this flat portion extending upward from the mouth of the socket any desired distance. The exterior face of the socket above the collar or thickened portion 13 is also formed with 110

a flat face 16 and it will be seen by reference to Fig. 3 that the side edges of the interior face 15 and the side edges of the outer flat face 16 are so disposed that these side edges will be intersected by radial planes extending from the axial center of the socket. According to my invention there are a plurality of sockets for each set, graduated according to size and so proportioned that a socket of 10 a certain size will fit snugly into the bore of a socket of a size larger, with the flat outer face of the socket A in Fig. 1 coinciding with the flat inner face 15 of the bore of socket B. This socket B may in turn be 15 inserted in the bore of a third socket and so on, the flat outer faces of the several sockets engaging with the flat inner faces of the bores of the several sockets and thus a rotation of one of the sockets will cause a rotation of all the other sockets. In each case 20 the extremities 11 of one socket will intersect the slot 14 of the next larger socket so that a drifting tool may be inserted in the slot 14 to drive one socket out of another. 25 With the construction above described, drills from which the tank or shank is broken can be readily used up to the last possible point of service. With regard to the reinforced mouth of the socket, it may 30 be stated that the socket now in use which is made without a reinforced mouth frequently splits at the mouth and as soon as this happens it becomes worthless. By reinforcing the mouth as I have done there is 35 little chance of the socket splitting and in fact the drill would probably break before the socket splits.

As before stated, the drill holding sockets now used in association with the round sockets has a bore flattened on one side in which 40 the drill is disposed, this drill socket, however, does not have any flattened exterior surface but is circular in cross section. There 45 is a single drill socket for each size of drill used and this requires that there be associated with the drill sockets, a series of round sockets, each having a circular interior surface, like the exterior of the socket, to line the drill. This series of round sockets is in

creases in size to the size necessary to engage the drill press, thus in use with a set of five different sizes of drill holding sockets, there must be associated five of the old round sockets in order that they may be nested one within the other in reducing to the size of 55 the drill to be used.

In my invention, the exterior of each socket from the reinforced mouth has exactly the same form in cross section as the interior of the socket into which it nests, thus in a 60 set of five drill sockets made in accordance with my invention, only five sockets will be necessary, while in a set composed of the old round sockets and the drill holding sockets, there must be ten sockets to a set. 65

There are a number of different drill presses in which, the drill spindles are of different sizes and for each of these different sizes, there must be a complete set of sockets, usually ranging from three to five sockets to a set. In each of these sets, as now used, there is one socket with a circular interior face to each one having a flattened interior face, making, therefore, in a three socket set, six sockets, and in a four socket 70 set, eight sockets, and in a five socket set, ten sockets, all told. This inconvenience and expense is entirely done away with in my invention.

Having described my invention, what I 80 claim is:

A drill socket having a tapered hollow body, the bore of the body being tapered and formed to provide a longitudinally extending flat face, the exterior face of the 85 body having a flat portion corresponding in position to the flattened face of the bore, the side edges of the interior flattened face and the side edges of the outer flattened face being so disposed as to be intersected 90 by common planes extending radially from the axial center of the socket.

In testimony whereof I hereunto affix my signature in the presence of two witnesses.

JOHN F. GRABILL.
